TRANSPOSING TRACKER BAR

Original Filed June 5, 1920

Robert Head Inventor
By his Attorney

P. W. Scherzer

UNITED STATES PATENT OFFICE.

ROBERT HEAD, OF YONKERS, NEW YORK, ASSIGNOR TO THE AEOLIAN COMPANY, A CORPORATION OF CONNECTICUT.

TRANSPOSING TRACKER BAR.

Application filed June 5, 1920, Serial No. 386,897. Renewed May 1, 1922. Serial No. 557,784.

To all whom it may concern:

Be it known that I, ROBERT HEAD, a citizen of the United States, and a resident of the city of Yonkers, State of New York, have invented certain new and useful Improvements in Transposing Tracker Bars, of which the following is a specification.

My present invention relates to transposing mechanisms for automatic player pianos and the like.

The objects of the invention are to provide a simple and practical device of this character, which can be readily operated to quickly transpose the playing from one key to another and in which the transposition will be accomplished without affecting the automatic controls for the pedals, expression and the like.

One of the special features of the invention is the construction of the tracker board with a slidable section carrying the note ducts and the provision of mechanism by which this slidable note duct section can be readily shifted with respect to the automatic controls on the stationary part of the tracker board.

Various other features of the invention will appear as the specification proceeds.

In the drawing accompanying and forming a part of this specification, I have illustrated the invention embodied in one of its simple, practical forms but wish it understood that the same may be modified in various respects without departure from the true spirit and scope of the invention as herein defined and claimed.

Figure 1 in the drawing referred to is a front or face view of a tracker board having the features of the invention incorporated therein, the middle or intermediate portion of the tracker board being indicated as broken away.

Figure 2 is an edge and longitudinal sectional view of the tracker board as taken substantially the plane of line 2-2 of Figure 1.

Figure 3 is a cross sectional view of the board on substantially the plane of line 3-3 of Figure 1, to show the construction of the control or shifting means.

Figure 4 is a sectional view across the middle portion of the tracker board as on substantially the plane of line 4-4 of Figure 1.

The tracker bar 5 differs from the usual

tracker bar mainly in the fact that it is constructed with a longitudinally extending slot 6 in the intermediate or note controlling section thereof, in which is seated a movable note duct slide 7.

This slide carries a complete set of note ducts 8 standing in the plane of the tracking surface and is shown as supported by means of ribs or flanges 9 at the back thereof, working in corresponding mortises 10 provided at the edges of the receiving slot, the slide being thus confined in its seat by the overlying flanges or guide plates 11.

In the particular construction herein disclosed, the slide is constructed at its opposite ends with extensions 12 of reduced width and the slot is similarly formed with extensions 13 at its opposite ends of reduced width to receive the end extensions 12 of the slide. This construction reduces the amount of cutting away of the tracker bar, assists in the proper guiding of the slide and also provides a supporting portion on the tracker bar adjacent the reduced slot extensions for the stationary control ducts 14. These ducts, in this particular illustration, are for dynamic control and four of them are shown provided at each end of the guide slot in position directly above the reduced extensions of the guide slot.

The tracker bar is usually provided with other relatively stationary control ducts. In this particular illustration there are two relatively fixed ducts 15 at the left hand end of the tracker and a third at the right hand end of the tracker for the so-called "automatic rewind" and "pedal controls" and there are also provided two so-called "Themodist" or expression control ducts 16 directly adjacent the opposite ends of the guide slot in the tracker bar.

The note duct slide is shifted for transposing purposes by means consisting in the illustration of the swinging handle lever 17 projecting through a slot 18 in the face of the tracker bar at one end, beyond the tracking surface thereof and pivoted at 19 at its rearward or inner end on a supporting bracket 20 secured to the back of the tracker bar.

This lever is preferably so connected with the note duct slide that each operation of said lever will serve only to "step" the note duct slide one note. This result is accom-

plished in the illustration by pivoting a double-ended pawl 21 on the lever at 22 and by causing said pawl, in the swinging movement of the lever in opposite directions, to be rocked so as to engage one or the other end thereof with the teeth of a gear-toothed element, shown as a rack 23 directly secured to the back of the slide as by means of a screw or screws 24.

10 The means for thus automatically rocking the ends of the pawl into engagement with the gear teeth consists in the disclosure of relatively stationary guides or abutments in the form of the springs 25 situated

15 adjustments in the form of the springs 25 supported on the bracket at 26, at opposite sides of the swinging lever and arranged to engage with their forward ends the inclined cam surfaces 27, 28 on the back of the double-ended pawl.

20 This operation will be clear from Figure 2, in which it will be seen that as the lever is shifted in a right handed direction, the left hand end of the pawl will travel away from the left hand spring 25 and the right hand cam surface 28 bearing against the right hand spring 25 will cause the pawl to be rocked so as to carry the right hand end thereof into engagement with the adjacent tooth of the rack.

30 The parts are so designed that the full swinging movement of the lever either to the right or to the left from the intermediate position shown, will accomplish a shifting of the note duct slide sufficient only to transpose by a semi-tone. This prevents the slide being shifted suddenly throughout a range of keys and also prevents the slide being left at an intermediate point between two different keys. At the same time, it is an easy matter to shift the transposing slide step-by-step through the complete range of keys, by repeatedly reciprocating the swinging operating handle to the left from its middle position shown in Fig. 2, or vice versa by repeated reciprocations of the handle to the right from its said middle position.

50 31 is a stationary pin projecting from the supporting bracket 20 through a slot 22 in the hand-lever 17. The length of this slot, therefore, determines the throw in either direction of the hand-lever and consequently determines the distance to which the nozzle-slide is shifted by each reciprocation of the hand-lever.

The hand-lever is normally returned to its intermediate or neutral position by a returning spring 29 shown as supported on the lever pivot 19 and as having forwardly extending spring arms 39, extending to opposite sides of and bearing on the pawl pivot-pin 22. This spring, it will be evident, tends to centralize the hand-lever wherein it is assisted by the aforesaid stationary pin 31 projecting through the slot 32 in

the lever and standing in between the two spring arms 30.

The invention is extremely practical for the purpose intended. Transposing means in a player-piano is primarily useful in playing song-rolls in order to raise or lower the musical key to suit the singer's voice. In playing other rolls, such, for instance, as artist-played rolls having side perforations embodying the dynamics with which the composition was rendered, the note-duct bar will be adjusted into the centralized normal position in Fig. 1 so that none of the note-ducks of the slide is in line with the dynamics control ducts 14. 70 75 80

Any well-known means (not shown) will be provided to render the dynamics ducts 14 operative or inoperative, depending respectively upon whether an aforesaid artist roll is to be played without transposition; or a song-roll with transposition. 85

What I claim is:

1. In transposing mechanism for automatic players, a tracker having a longitudinal slot and a fixed control duct adjacent the end of the same and a slide bar longitudinally shiftable in said slot and provided with note ducts. 99

2. In transposing mechanism for automatic players, a tracker bar provided with a longitudinal slot having extensions of reduced width at opposite ends of the same, a bar slidably fitting in said slot and provided at opposite ends of the same with projecting tongues of reduced width slidably fitting in the reduced end extensions of the slot and note ducts in said slidable bar. 95 100

3. In transposing mechanism for automatic players, a tracker bar provided with a longitudinal slot having extensions of reduced width at opposite ends of the same, a bar slidably fitting in said slot and provided at opposite ends of the same with projecting tongues of reduced width slidably fitting in the reduced end extensions of the slot, note ducts in said slideable bar and relatively stationary control ducts in the tracker bar adjacent the reduced end extensions of the slot. 105 110

4. In automatic players, a tracker bar, a slide movably mounted in said tracker bar and provided with ducts, the tracker bar having a slot therein at one side of the note-sheet path and a handle operatively connected with the slide extending through said slot. 115 120

5. In automatic players, a tracker bar, a slide movably mounted in said tracker bar and provided with ducts, the tracker bar having a slot therein at one side of the note-sheet path and a handle extending through said slot, and having a pawl and rack connection with the slide for operating the slide with a stepped movement. 125

6. In an automatic player, a tracker bar 130

having a movable section, a shifting handle therefor and a pawl and rack connection between said handle and movable section.

7. In an automatic player, a tracker bar having a movable section provided with a rack, an operating handle having a pawl for engagement with the teeth of said rack, said pawl being pivoted intermediate its ends and means for automatically engaging one or the other of said ends with the rack as the handle is shifted in opposite directions.

8. In an automatic player, a tracker bar having a movable section provided with a rack, an operating handle, a double-ended pawl carried by the handle, means for automatically returning the handle to a neutral position and means for carrying one or the other of the ends of the pawl into engagement with the rack as the handle is shifted in opposite directions.

9. In an automatic player, a tracker bar having a movable section provided with a rack, an operating handle, a double-ended pawl carried by the handle, means for automatically returning the handle to a neutral position, means for carrying one or the other of the ends of the pawl into engagement with the rack as the handle is shifted in opposite directions, and means for limiting the throw of the handle in both directions.

10. In an automatic player, a tracker bar having a movable section provided with a rack, an operating handle, a double-ended pawl carried by said handle, a pin on said handle, a centralizing spring having opposed spring arms engaging said pin, a center stop between said spring arms, and relatively stationary springs engaged by the ends of the pawl as the handle is shifted in opposite directions.

11. In an automatic player, a tracker bar having a movable section provided with a rack, an operating handle, a double-ended pawl carried by said handle, and relatively stationary springs engaged by the ends of the pawl as the handle is operated in opposite directions to carry same into engagement with the rack, said pawl having inclined cam shoulders engaged by said springs.

12. In an automatic player, a tracker bar having a movable section, a supporting bracket at the back of said tracker bar, a shifting handle for said movable section pivoted on said bracket, a double-ended pawl carried by said handle, a gear-toothed element connected with the movable section of the tracker and adapted to be operatively engaged by the pawl, means for carrying one end or the other of the pawl into engagement with the gear-toothed element as the handle is shifted in opposite directions and means for automatically returning the handle to a neutral position.

13. Shifting means for tracker mechanism comprising an operating handle, a double-ended pawl carried by said handle, a pin carried by the handle, a centralizing spring having opposed spring arms engaging said pin, relatively stationary springs arranged to bear on opposite ends of the double-ended pawl and a gear-toothed element arranged to be operatively engaged by the ends of said pawl.

14. In transposing mechanism for automatic players, an operating handle, a double-ended pawl mounted on said handle, a gear element engageable by said pawl and connected with the shiftable section of the transposing mechanism and relatively stationary means engageable by the pawl in the movement of the handle in opposite directions to throw the opposite ends of the pawl into engagement with the gear element.

15. In transposing mechanism for automatic players, a tracker bar having a fixed control duct, a shiftable member having note ducts, and means for shifting said member step by step to effect transposition.

16. In transposing mechanism, a tracker comprising an endwise shiftable note-duct section, a relatively stationary control-duct in the path of the endwise travel of said note-duct section but separated therefrom by a space when said note-duct section is in its normal non-transposing position, and other relatively stationary control-ducts extending along the side of said space to one side of the path of the note-duct section whereby said last named control-ducts will be above or below said space when the tracker is horizontal.

17. In transposing mechanism, a tracker comprising an endwise shiftable note-duct section, a relatively stationary control-duct separated by a space from the end of the note-duct section when the latter is in its normal non-transposing position, and other relatively stationary control-ducts extending along the side of said space to one side of the path of the note-duct section whereby said last named control-ducts will be above or below said space when the tracker is horizontal.

18. In transposing mechanism, a tracker comprising an endwise shiftable note-duct section, a relatively stationary control-duct separated by a space from the end of the note-duct section when the latter is in its normal non-transposing position, and other relatively stationary control-ducts extending along the side of said space to one side of the path of the note-duct section whereby said last named control-ducts will be above or below said space when the tracker is horizontal, and means for rendering said last named control-ducts inoperative at will.

19. In transposing mechanism for automatic players, a slide provided with note ducts and supported so as to be longitudi-

nally shiftable; relatively stationary control ducts supported to one side of the path of the said slide so that the end note ducts in said slide can be brought into and out 5 of transverse juxtaposition with said control ducts.

20. In transposing mechanism for automatic players, a slide provided with note ducts and supported so as to be longitudinally shiftable; relatively stationary control

ducts supported to one side of the path of said slide so that the end note ducts in said slide can be brought into and out of transverse juxtaposition with said control ducts; and means for rendering inoperative said 15 control ducts.

In witness whereof, I have hereunto set my hand this 28th day of May, 1920.

ROBERT HEAD.
